CLAIM

The ornamental design for a friction welding tool for thermoplastic straps or similar article, as shown and described.

DESCRIPTION

FIG. 1 is a front and left side perspective view of the friction welding tool for thermoplastic straps or similar article showing my new design;

FIG. 2 is a rear, bottom and right side perspective view thereof;

FIG. 3 is a top, left side perspective view thereof;

FIG. 4 is a top, right side perspective view thereof;

FIG. 5 is a top plan view thereof; and

FIG. 6 is a front perspective view thereof.

FIG. 1

FIG. 2

FIG. 3

FIG. 5

FIG. 6
